Harold W. Thompson

UNITED STATES PATENT OFFICE.

FREDERIC V. HETZEL, OF INDIANAPOLIS, INDIANA, ASSIGNOR TO LINK-BELT COMPANY, OF CHICAGO, ILLINOIS, A CORPORATION OF ILLINOIS.

ROLLER OR LIKE MACHINE PART.

1,372,509.

Specification of Letters Patent. Patented Mar. 22, 1921.

Application filed January 11, 1919. Serial No. 270,696.

To all whom it may concern:

Be it known that I, FREDERIC V. HETZEL, a citizen of the United States, and a resident of Indianapolis, county of Marion, State of Indiana, have invented certain Improvements in Rollers or like Machine Parts, of which the following is a specification.

My invention relates to certain improvements in wheels, rollers, and like machine parts, in which there is a rim having a chilled surface, and a hub, also having a chilled surface.

One object of my invention is to design the roller, or other element, so that the chill mandrel for the hub can be readily withdrawn, leaving an opening with parallel sides.

A further object of the invention is to make a roller, or other machine element, having a chilled periphery, and a chilled hub, in which the bore can be made of an even diameter throughout.

In the accompanying drawings:

Figure 1 is a side view of a roller illustrating my invention;

Fig. 2 is a sectional view on the line 2—2, Fig. 1;

Fig. 3 is a perspective view of the hub, showing the cracks made therein, due to the breakage of the parts;

Fig. 4 is a side view illustrating a hub in which a rectangular opening is formed;

Fig. 5 is a face view of a plate wheel illustrating my invention; and

Fig. 6 is a view illustrating a modification of the invention.

In the present instance, 1 is a roller adapted to travel on a track and arranged to support conveyer or other chains. This roller 40 has a rim 2 and a flange 3. The surface 4 of the flange, as well as part of the rim, is chilled in the ordinary manner. 5 is a hub and 6, 6 are spokes extending from the rim to the hub. These spokes may be made in any suitable manner and are preferably made as shown in Fig. 1. Each side of the hub 5 is recessed, in the present instance, as at 7, leaving a comparatively narrow web 8. The internal surface 9 of the hub is chilled 50 and the opening 10, formed in the hub, is of an even diameter throughout.

In ordinary practice, if a chill mandrel of an even diameter throughout be used, it is impossible to withdraw the mandrel from the hub without destroying it, owing to the

shrinkage of the parts onto the mandrel. In some instances, the opening may be made by providing the mandrel with a considerable taper. This is objectionable, as it is difficult and expensive to grind or bore the chilled hub so as to provide an opening of an even diameter to allow the roller to rotate freely on a pin.

I have found that by making the recesses in the hub, as at 7, which reduce the inner 65 wall at one or more points to a mere shell, that when the roller, or other machine element, cools, it will crack the web or webs 8, and this cracking or parting of the hub allows for the withdrawal of the mandrel. 70 The cracking of the hub does not materially reduce the strength of the roller, nor does it interfere with its travel on the spindle, or pivot pin. The result is that I obtain a true hardened bearing.

By making the roller, as indicated in Fig. 1, where the hub is made in two sections connected together by narrow webs, and by arranging substantial spokes to support each section, the strength of the roller is not impaired to any appreciable extent and its life is prolonged, due to the chilled surface at the hub, as well as at the periphery.

While I have shown a cylindrical opening in the hub, as in Fig. 1, the opening may be 85 of any shape desired. In Fig. 4, I have illustrated a rectangular opening.

In some instances, a single slot may be made to form one weak spot, or more than two slots may be made, if desired, depending 90 upon the size and character of the hub.

While I have shown a roller having a chilled rim and a chilled hub, the chilled rim may be dispensed with in some instances, but it is highly desirable to make 95 this hub in the manner shown where there is a chilled rim, as the rim has a tendency to shrink, and, as its surface is more extended than that of the hub, it tends to contract the hub and bind the chill mandrel 100 therein.

Instead of the spokes, a plate may be used to connect the rim and the hub, as shown in Fig. 5, and the wall may be made with a single or a double plate, as desired.

In Fig. 6, I have shown the hub having three perforations 7^a, which form the webs 8^a in the hub, and these may be formed by cores in the ordinary manner so that when the roller, or other machine element, cools, 110

the hub will be cracked at these points and the chill mandrel can be readily withdrawn.

By the above construction, it will be seen that I am enabled to make a roller, or other element, having a rim and hub, in which the periphery of the rim is chilled, as well as the wall of the pivot pin opening in the hub.

I claim:

1. A roller, or like machine element, having an integral hub and rim, said hub having a longitudinal opening therein, the walls of the opening in the hub being chilled, and the hub being reduced at one or more points to form a weak portion, so that as the hub

expands during cooling, it may crack to allow for the withdrawal of the chill mandrel.

2. A roller, or other machine element, having a rim and hub in the form of an integral casting, the hub having a longitudinal opening therein of an even diameter throughout, the periphery of the rim and the walls of the opening being chilled, and the hub being reduced at one or more points to form a weak portion or portions, the hub being cracked at the weak portions to allow for the removal of the chill mandrel.

In witness whereof I affix my signature.

FREDERIC V. HETZEL.
